UNITED STATES PATENT OFFICE.

WILLIAM D. McATLIN, OF TULLVANIA, MISSOURI, ASSIGNOR OF ONE-HALF TO JOHN H. McCONNELL, OF ADAIR, MISSOURI.

HAY-STACKER.

No. 841,094.

Specification of Letters Patent.

Patented Jan. 8, 1907.

Application filed January 27, 1906. Serial No. 298,219.

To all whom it may concern:

Be it known that I, WILLIAM D. McATLIN, a citizen of the United States, residing at Tullvania, in the county of Macon and State 5 of Missouri, have invented certain new and useful Improvements in Hay-Stackers, of which the following is a specification.

The object of my invention is to provide an improved hay-stacker designed to receive a 10 predetermined amount of hay and throw it upon a stack or into a wagon.

The present embodiment of my improved hay-stacker is illustrated in connection with an improved construction of horse-power 15 which is the basis of another application, a divisional from this application, such other application being Serial No. 311,580, filed on or about the 13th day of April, 1906.

For a full description of the invention and 20 the merits thereof and also to acquire a knowledge of the details of construction of the means for effecting the result reference is to be had to the following description and accompanying drawings, in which—

25 Figure 1 is a top plan view of my invention. Fig. 2 is a detail perspective view illustrating one set of sectional braces or straps 12. Fig. 3 is a perspective view of the hay-stacker proper, with parts in discharging or upright 30 position. Fig. 4 is a transverse sectional view of the horse-power mechanism designed for use with the hay-stacker of my invention, the section being taken approximately on the line $x-x$ of Fig. 8, the parts being in normal 35 position. Fig. 5 is a sectional view of the hay-stacker with the parts of the fork extended. Fig. 6 is a detail perspective view of the lower end of one of the fork-arms and the adjustable brace therefor. Fig. 7 is a 40 detail perspective view of the tumbling-rod and its adjustable mounting.

Corresponding and like parts are referred to in the following description and indicated in all the views of the drawings by the same 45 reference characters.

The stacker proper comprises a framework 1, including two side bars 2, that constitute, in effect, sled-runners upon which the stacker may be moved from one place to another. 50 The framework is provided with suitable diagonal braces, as shown. The shaft 3 is journaled at its ends in cross-bars 4 of the framework 1 and extends longitudinally thereof and is mounted to rock back and forth upon

its longitudinal axis. The shaft 3 has rigidly 55 secured to it two standards 5, one near each end of the shaft. The standards 5 are each formed of two spaced-apart members 5^a, extending radially from the shaft and rigidly secured thereon by means of a box 5^b. Between the free ends of the spaced members 5^a of the standards 5 are slidably mounted bars 6, which also extend radially, as shown, and are preferably guided in a longitudinal movement with respect to the standards by means 65 of loops 7 and 8, embracing the parts, as shown. The bars 6 at their outer ends carry a series of tines 9, which are all rigidly connected together. The transverse rod 10 extends across and is secured to the rear end of 70 the tines 9, and upon this rod there is secured a second set of tines 11. The tines 11, in combination with the tines 9, constitute the hay-receiving portion of the stacker or 75 the fork upon which the hay is deposited preparatory to being thrown on the stack or into a wagon or the like. The set of tines 11 is pivotally mounted on the shaft 10, so as to be permitted to move toward and from the set of tines 9, and to limit the movement of 80 the tines 11 in one direction I have provided two pairs of straps 12. One strap of each pair is connected to a diagonal brace 13, extending from one of the bars 6 to the shaft 10, while the other strap of the said pair is attached to a cross-bar 11^a, secured to the tines 11. Both straps of each pair are provided 85 with slotted ends 14, that are slidably connected together, so that the pairs of straps may be extended to a certain definite limit, 90 and thereby permit a proportionate movement of the pivoted tines 11.

As has before been stated, the bars 6 are longitudinally slidable with respect to the standards 5 which carry them, and by this 95 means the hay-receiving fork is rendered extensible. When the bars 6 are slid outwardly on the standards 5, they may be retained rigidly in such extended position by means of stirrups 15, that are pivotally secured to the 100 loops 7 and are designed to turn over into engagement with the outer ends of the outermost members 5^a of the standards 5. Truss-rods 16 are secured at one end in posts 17, mounted in the outer ends of the bars 6, and 105 the other ends of said truss-rods 16 are provided with loops 18. From the bases of the standards 5 there project two posts 19, on

each of which there is mounted an eccentrically-fulcrumed band-lever 19^a, each of which is provided with a notch 19^b, designed for the accommodation of the loops 18. From the foregoing it is to be understood that when the hay-receiving fork is extended to its limit the loops 18 are in the notches 19^b of the levers 19^a, and the latter are then turned down or inwardly past their centers to snap into locked position, and thereby securely hold the truss-rods in taut position. Each truss-rod 16 comprises two members 16^a and 16^b. The member 16^a is provided at one end with a loop 18, before described, and is provided at its other end with an eye 20, slidably engaging the other member 16^b. When the fork is extended and the loop 18 engaged by the hand-lever 19^a, before mentioned, the eye 20 of the member 16^a will bring up against the shoulder 20^a on the member 16^b. When, on the other hand, it is desired to hold the fork in a radially-contracted position at the inner limit of the relative movement with respect to the standards 5, another loop 21, formed on the member 16^b, is detachably connected to the hand-levers 19^a, while the other members 16^a may be entirely free from said levers. It will thus be seen that each truss-rod 16 is adjustable or extensible in character to accommodate itself to two different positions (contracted and extended) of the fork with respect to its standards.

22 designates springs the action of which tends to return the hay-receiving fork to an approximately vertical position to throw the load of hay thereon onto the stack or into a wagon. In the present instance the springs 22 are arranged in two pairs, one pair for each of the standards 5. Also in the present instance each spring comprises coiled portions 22^a, wound around the shaft 3 or a sleeve, boss, or the like on said shaft, and two diverging ends 22^b, one of which is connected to a side bar 2 of the framework 1 or some other specific part of the framework, while the other end is connected to a spool, thimble, or roller 23, mounted between the spaced members 5^a of the standards 5 and guided therein by means of side plates 23^a. As shown in the drawings, the posts 19 preferably extend entirely through the standards and have secured to their ends diagonal braces 24. The braces 24 are also secured at opposite ends to the standards 5 at the outer ends of the latter.

In the practical operation of the stacker the framework 1 is moved to the desired point in the field and the hay-receiving fork is adjusted to the desired extension. By means of my improved horse-power and tumbling-rod, which I shall shortly describe, the shaft 3 is rocked back and forth. It is first turned in one direction against the action of the springs 22, so as to carry the hay-receiving fork downwardly in such a position rela-

tive to the ground that the hay may be slipped thereon. When this operation has been completed, the shaft 3 is turned backwardly in a direction to relieve the springs 22 of their tension and in a direction also to lift the hay-receiving fork so that it will deposit its load upon the stack or in a wagon or the like. It is to be particularly noted that the tension of the springs 22 is to raise the hay-receiving fork. Hence the strain upon the horses is equalized, as the exertion that is required to depress the hay-receiving fork when moving the same in a downward direction is substantially compensated for by the springs 22 when force is exerted to raise the loaded fork into position to dump its load.

The tumbling-rod construction for actuating the stacker proper is, according to the present embodiment of my invention, incorporated in a horse-power forming the basis of my other application before referred to and which I shall now proceed to describe.

Upon the framework 25, consisting of side bars and sled-runners 26, connected to cross-bars 27 by diagonal members 28, there is mounted a carriage 29. The carriage 29 is mounted to slide back and forth on the framework 25, and in the present instance the means whereby this movement is provided comprises sleeves 30, that encircle and are slidably mounted upon the cross-bars 27. To effect the movement or actuation of the carriage, I have provided a screw-rod 31, mounted to turn in a suitable bearing 32 on one of the side bars 26, but held from longitudinal movement thereon, the said screw-rod working through a correspondingly-formed bearing 33 in a cross-bar 34 of the carriage. By means of a spanner or some similar tool applied to the polygonal nut 35 of the screw-rod the latter may be turned so as to move the carriage in one direction or another upon the framework 25.

The tumbling-rod 36 is connected by universal joints 37 to the shaft 3 of the stacker proper, the said joints being preferably gimbal-joints, one or more spindles of which are detachable, so that the parts may be disconnected or coupled together whenever desired. Connecting-rod 38 may be also introduced into this gearing, so that the tumbling-rod 36 may be located at a convenient distance from the stacker proper. The tongue 39 of the tumbling-rod 36 is preferably bifurcated at one end to encircle the tumbling-rod and is pivotally connected thereto, so that it may rock the same from side to side. The tongue 39 is provided at its other end with a boxing 40, in which it is mounted to freely turn both axially and longitudinally. The boxing 40 is provided at its sides with trunnions 41, which are pivotally mounted in a sliding cross-head 42. The cross-head 42 is mounted in and between guide-bars 43 and is susceptible to movement thereon, and

it is formed at one end with a transverse bearing 44, in which a threaded adjusting-rod 45 is mounted. The rod 45 is also mounted with a swivel connection in a bearing 45^a, secured to the bars 43 near one end of the latter. Near the opposite end of the bars 43 there is pivotally mounted a lead-pole 46, arranged to be swung in a vertical plane, so that it may extend out horizontally or be 5 swung up into a vertical position out of the way. The guide-bars 43 are rigidly secured to a ring 47, which is mounted to rotate upon an annulus 48, supported on the carriage 29 and positioned horizontally. Also rigidly 10 secured to the ring 47 are spaced-apart beams 50, between which a lever 51 is mounted to slide longitudinally, so that it may be extended more or less. The lever 51 is the lever to which the horse or horses are attached 15 to actuate the horse-power. Braces 52 and 53 are secured to the beams 50 and the beams 43, so as to render the parts rigid.

When the horse-power is coupled to the stacker proper and the former is turned by 20 means of the lever 51, it is evident that the tongue of the tumbling-rod will turn the shaft 3 of the stacker proper in one direction through one-half the revolution or turning movement of the horse-power and will then 25 turn the said shaft 3 backward during the remaining half of said movement. By this means as the horses move around the framework 25 the hay-receiving fork will be first lowered to receive its load and then raised to 30 deposit the same.

It is to be particularly noted that the carriage 29 may be moved to different positions along the supporting-framework 25, so as to shift the carriage to compensate with the position of the framework 1 and the shaft 3, so 35 that the tumbling-rod and said shaft may be always arranged in the proper alinement. It is also to be understood that the cross-head for the tongue of the tumbling-rod may be shifted or adjusted to different positions, so as to vary the pitch of the tumbling-rod, and consequently also the pitch or throw of the 40 hay-receiving fork.

Having thus described the invention, what 45 is claimed as new is—

1. A hay-stacker, comprising a support, an oscillating hay-receiving fork mounted on said support, and springs tending to swing said hay-receiving fork upwardly.
2. A hay-stacker, comprising a support, an oscillating hay-receiving fork on said support, springs tending to move said fork to a vertical position on the support, and means for depressing said fork.
3. A hay-stacker comprising a support, oscillating standards mounted on said support, means for oscillating the same, a hay-receiving fork extensibly mounted on said standards and provided with stirrups designed to 55 take over the ends of the standards whereby

to hold the fork in an extended position thereon, and an adjustable truss-rod connecting said fork and standards.

4. A hay-stacker comprising a support, oscillating standards mounted on said support and means for oscillating the same, a hay-receiving fork extensibly mounted on said standards and provided with means for holding the fork extended on the standards, and truss-rods connecting the fork and standards, said truss-rods being provided with two members adjustably connected together as and for the purpose set forth.

5. A hay-stacker comprising a support, oscillating standards mounted on said support and means for oscillating the same, a hay-receiving fork extensibly mounted on said standards and provided with means for holding the fork extended on the standards, and truss-rods connecting the fork and standards said truss-rods being constructed in two members adjustably connected together and of different lengths, each of such members being arranged for engagement with a stationary part of the standards.

6. A hay-stacker comprising a support, oscillating standards mounted on said support and means for oscillating the same, a hay-receiving fork extensibly mounted on said standards, means for holding said fork extended on the standards, longitudinally-adjustable truss-rods connected to said fork and a detachable connection between said truss-rods and the standards, as and for the purpose set forth.

7. A hay-stacker, comprising a support, oscillating standards mounted on said support and means for oscillating the same, a hay-receiving fork extensibly mounted on said standards, truss-rods connected to said fork and embodying two adjustably-connected members each of which is provided at one end with a loop and eccentric levers mounted on said standards and arranged for detachable connection with the lever of each member.

8. A hay-stacker, comprising a support, a shaft mounted on said support and designed to be rocked back and forth about its longitudinal axis, a hay-receiving fork carried by 115 said shaft and embodying standards radially extended from the shaft, and springs coiled around said shaft and secured to the support at one end and to the standards at their other ends, as and for the purpose set forth.

9. A hay-stacker, comprising a support, a shaft mounted in said support and arranged to be rocked back and forth about its longitudinal axis, standards secured to said shaft and extending radially therefrom, said 125 standards being spaced from each other, a hay-receiving fork provided with bars slidably mounted between the members of the standards, and springs coiled around said shaft one end of said springs being secured to 130

the support and a spool mounted between spaced members of the standards and secured to the other ends of said springs.

10. In a hay-stacker the combination of an oscillating hay-receiving fork, and a tumbling-rod connected therewith.

11. In a hay-stacker the combination of a shaft mounted to be rocked back and forth, a hay-receiving fork carried by said shaft and oscillated by the movement thereof, and a horse-power embodying a tumbling-rod connected to said shaft, as and for the purpose set forth.

12. A hay-stacker comprising a support, an oscillatory hay-receiving fork mounted on said support, means for oscillating said fork, the fork being provided with a set of sta-

tionary tines, a set of pivoted tines arranged to move toward and from the stationary tines, and longitudinally-adjustable straps arranged in pairs the outer ends of the respective straps of each pair being secured respectively to the set of pivoted tines and to some stationary portion of the fork, and the adjoining ends of said straps having an inter-engaging slotted connection, whereby they may move freely on each other in one direction.

In testimony whereof I affix my signature in presence of two witnesses.
